UNITED STATES PATENT OFFICE.

CARL HAMBUECHEN, OF BELLEVILLE, ILLINOIS, ASSIGNOR, BY MESNE ASSIGNMENTS, TO NATIONAL CARBON COMPANY, INC., OF CLEVELAND, OHIO, A CORPORATION OF NEW YORK.

BATTERY HAND-LAMP.

1,377,477.

Specification of Letters Patent. Patented May 10, 1921.

Application filed April 13, 1917. Serial No. 161,704.

To all whom it may concern:

Be it known that I, CARL HAMBUECHEN, a citizen of the United States, and resident of Belleville, county of St. Clair, and State 5 of Illinois, have invented certain new and useful Improvements in Battery Hand-Lamps; and I do hereby declare the following to be a full, clear, and exact description of the invention, such as will enable 10 others skilled in the art to which it appertains to make and use the same.

The present invention relates to lamps or lanterns having an electric light energized from a battery, and having switch mechanism whereby the lamp may be lighted or extinguished at the will of the operator.

The present invention relates more particularly to such details of construction and such general assembly of the several parts 20 as will permit the device to be roughly handled. The preferred embodiment of the invention can be carried in a kit of metal tools without danger of inadvertently lighting the lamp through accidental connection of exposed conductive parts of the structure.

It is a further object of the invention to protect the base of the lamp and more particularly its inner or central terminal from 30 un-due pressure or end thrust, such as might result from hammering of the battery thereon when the device is dropped. To effect this result, I make connection with the central lamp terminal through yielding contact 35 means, and the hammer or thrust of the battery is borne by the reflector and not by the base of the lamp.

It is a further object of the invention to provide a construction whereof the several 40 parts are easy to make by ordinary metal-working operations, and when once assembled, are reliable in action and not liable to disarrangement when in the hands of persons not familiar with the principles of electricity.

The foregoing and other objects and advantages of the present invention are made clear by the following description, which is to be taken in conjunction with the accompanying drawings, wherein—

Figure 1 is a sectional elevation of a hand lamp embodying the present invention and having a metal casing wherein the lamp and battery are housed.

Fig. 2 is a similar view of an embodiment 55 wherein the casing is for the most part of insulating material.

Figs. 3 to 7 are details of certain of the parts used in the switch mechanism of Fig. 1 or 2.

Fig. 8 is a sectional elevation of a modified form of hand lamp wherein certain features of the invention are incorporated, more particularly the means for protecting the lamp from the end thrust or hammering 65 of the battery.

Fig. 9 is an enlarged detail in section of the insulating base and contact member used for this purpose.

Fig. 10 is an enlarged plan view of this 70 base as viewed from the front.

Fig. 11 is a plan view of the spring.

In the embodiment illustrated in Fig. 1, the hand lamp comprises a tubular casing 1 of metal having at its bottom an integral 75 sleeve 2 with threads pressed therein whereon is threaded an end cap 3 carrying a helically coiled spring 4, for making electrical connection with the naked bottom of a dry battery 5, preferably of usual construction and consisting of a plurality of dry cells arranged end to end in a pasteboard tube.

At the other end of casing 1 is an integral threaded sleeve 6 to which is secured a collar 7, under the front flange of which is 85 secured a glass lens 8. A reflector 9 has an outwardly extending flange 10 which is seated against the end of sleeve 6 and is there clamped in position under lens 8. Threaded into a tubular extension of reflector 9 and having its outer terminal in electrical connection therewith in usual manner 90 is a lamp 11.

Threaded to the exterior of the reflector's tubular extension, or otherwise suitably secured thereto, is a base 12 of insulating material preferably of circular outline and constructed of indurated fiber or other strong tough material. Mounted on this base, as by a plurality of rivets 13, is a pair of contact 100 members 14 and 15, each of which is of annular shape and dished form. Contact member 14 has a cup at its center to receive the base of lamp 12, and at the bottom of the cup is provided with a spring contact finger 16 105 (Fig. 5) stamped up from a disk which is permanently secured in a swage at the bottom of the cup. It is this spring which is

relied on to protect the lamp against end thrust, as hereinafter recited.

Contact members 14 and 15 are spaced apart as by the ring of insulation 17 and insulating disk 18, and the rivets 13, whereby the contact members are held to base-plate 12, pass through openings in contact member 14 which are large enough to prevent electrical connection between the contact members through the rivets. Also, contact member 14 may be provided with a plurality of nipples 14' (Fig. 4) which enter holes in the insulating ring 17 and so prevent rotation of contact member 14 into engagement with the rivets. Contact member 15 is preferably made in two parts, as shown, the rear part 19 telescoping over the forward part and serving to extend that part far enough to contact with the central terminal 20 or carbon pole 20 of the dry battery.

With the several elements constructed and arranged as above described, the end thrust of the batteries due to the pressure of helical spring 4 is taken up by base-plate 12 and delivered to reflector 9 and thence to the screw threads of collar 10, and if the hand lamp be dropped, the hammering of the battery due either to its inertia or to the rebound from spring 4, will not tend to crush in the lamp bulb, for even though base 12 may shift forward along the threaded extension of reflector 9, due either to crushing of its threads or a loose fit, there will be enough play to spring contact 16 to protect the bulb of the lamp. This spring contact 16 is also of convenience in insuring a permanent connection to the inner or central lamp terminal whether the exterior threads on the lamp base do or do not exactly conform with the threads of the reflector, and when the lamp is once in place, the tension of the spring tends to prevent it from working loose or out of electrical engagement with its associated contact element.

As a means for bridging the gap between contact elements 14 and 15, there is provided a thumb-piece 21 mounted to slide longitudinally of the casing and attached as by rivets 22 to a metal strip 23, the forward end of which carries a contact blade 24 movable into the gap between contact elements 14 and 15 to bridge that gap and establish the flow of current from the inner battery terminal to the inner lamp terminal. This contact blade or element 24 may be insulated from metal strip 23 as by strips 25 and 26 of fiber riveted to the two parts to be connected. Fiber strip 25 preferably extends forward far enough to insure thorough insulation, from metal case 1, of the contact blade 24 and its connecting rivet.

In the modification illustrated in Fig. 2, the tubular casing 27 is of fiber, or other insulating material, provided at its bottom end with an attached threaded sleeve 28, and

at its front end with a similar sleeve 29. Throughout this figure, such parts as are common to Fig. 1 are numbered correspondingly.

Since casing 27 is non-conducting, there must be provided an electrical connection between the helically coiled spring 4 and the reflector at the other end of the casing. To effect this result, there is provided a metal strip 30 extending through the tube from end to end and having its rear end contacting with collar 28, and consequently in electrical connection with spring 4, and having its front end in contact with sleeve 29. In this way, one pole of the battery is permanently connected to the outer terminal of the lamp and the other or front pole of the battery can be connected with the inner terminal of the lamp through forward movement of thumb-piece 21 and its associated parts.

A battery hand lamp constructed as above described has the advantage that it can be placed in a tool kit among metal tools without danger of accidental lighting of the lamp through contact of exposed metal parts with metal tools in the kit. In this sense, the hand lamp is "non-short-circuiting."

In the modification illustrated in Fig. 1, all of the exposed metal parts are of the same polarity, viz., that of the bottom of the battery.

In the modification illustrated in Fig. 2, the metal fittings at the ends of the lamp are of the same polarity, viz., that of the bottom of the battery, and the metal thumb-piece 21 and the plate or shield 31 on which it slides are not in the circuit, and can be connected at will with the fittings at either end of the casing without affording a path for current from the battery.

In the modification illustrated in Figs. 3 to 11, inclusive, the lamp 32 is threaded into and protrudes beyond the reflector 33 in usual manner, and the reflector is clamped against the end of the casing and under lens 34 by collar 35, as in Figs. 1 and 2, and so serves as a rigid support for the lamp. The battery 36 is of usual construction and is urged toward the lamp by a coiled spring 37 carried in usual manner by the end cap 38. The other details of the casing are not important, for the novelty resides more particularly in the means whereby in a battery hand lamp of this general construction the lamp base is protected from the end thrust of the battery and from shocks and hammering incident to rough usage. The protective means comprises an insulating base 39 threaded or otherwise suitably secured to reflector 33 and carrying a contact member 40, preferably in the form of a flanged cup enveloping and completely inclosing the protruding end of the lamp and secured to

the base by a plurality of rivets 41. This contact member carries a spring 42 which yieldingly engages the inner lamp terminal and establishes electrical connection there-
 5 with when the inner or adjacent battery terminal 43 rests against the contact mem-
 ber 40, as shown in Fig. 8. Spring 42 may
 be in the form of a spring finger stamped
 10 up from a disk, as indicated in Fig. 11,
 and the disk may be permanently secured
 in a swage at the bottom of the cup, as
 shown in Fig. 9.

I claim:

1. In a hand lamp, the combination of
 15 a lamp, a battery, means connecting one pole
 of the battery with the outer terminal of
 the lamp and switch mechanism between the
 other pole of the battery and the inner ter-
 minal of the lamp, said mechanism com-
 20 prising annular contact members spaced
 apart, one of which has a spring yieldingly
 engaging the inner lamp terminal and the
 other of which engages the battery pole,
 and means for bridging the gap between
 25 said contact members when the lamp is to
 be lighted.

2. In a hand lamp, the combination of
 30 a lamp, a battery, means connecting one pole
 of the battery with the outer terminal of
 the lamp and switch mechanism between the
 other pole of the battery and the inner ter-
 minal of the lamp, said mechanism com-
 35 prising annular dished contact members
 spaced apart, one of which has a spring
 finger yieldingly engaging the inner lamp
 terminal and the other of which engages
 the battery pole, and means for bridging
 40 the gap between said contact members when
 the lamp is to be lighted.

3. In a hand lamp, the combination of a
 45 lamp, a battery, means connecting one pole
 of the battery with the outer terminal of
 the lamp and switch mechanism between the
 other pole of the battery and the inner ter-
 minal of the lamp, said mechanism compris-
 50 ing contact members spaced apart, one of
 which yieldingly engages the inner lamp
 terminal and the other of which engages the
 battery pole, means for bridging the gap
 between said contact members when the
 55 lamp is to be lighted, a thumb-piece for ac-
 tuating said bridging means, and a casing
 for said battery whereon said thumb-piece
 is mounted for movement longitudinally
 toward said lamp thereof.

4. In a battery hand lamp, the combina-
 60 tion of a casing, a battery and a lamp
 therein, means for connecting the bottom
 of said battery with the outer terminal of
 said lamp and switch mechanism between
 the inner terminal of said lamp and the
 65 upper terminal of said battery, said mecha-
 nism comprising contact members spaced
 apart, one of which has a spring finger yield-
 ingly engaging the inner lamp terminal and

the other of which engages the battery ter-
 minal, and a contact blade movable toward
 said lamp to connect said contact members
 when the lamp is to be lighted.

5. In a battery hand lamp, the combina-
 70 tion of a tubular casing, a battery and a
 lamp therein, an insulating base encircling
 the base of said lamp, a pair of dished con-
 tact members mounted on said base and
 spaced apart by insulating material, one of
 75 said members yieldingly engaging the inner
 lamp terminal and the other of said mem-
 bers contacting with the upper battery ter-
 minal, and means for bridging the gap be-
 tween said dished members when desired. 80

6. In a battery hand lamp, the combina-
 85 tion of a tubular casing, a battery and a
 lamp therein, means connecting one pole of
 the battery with the outer terminal of the
 lamp and circuit controlling means for con-
 necting the other pole of the battery with
 90 the inner terminal of said lamp, said circuit
 controlling means comprising contact mem-
 bers spaced apart, one of which yieldingly
 engages the inner lamp terminal and the
 other of which engages the adjacent battery
 95 pole, a conductor movable toward said lamp
 to bridge said space when the lamp is to
 be lighted, and a thumb-piece mounted to
 slide longitudinally of said casing and op-
 eratively connected to actuate said conduc-
 100 tor; substantially as described.

7. In a battery hand lamp, the combina-
 105 tion of a tubular casing, a metal cap secured
 to one end of said casing and carrying a
 contact spring, a collar secured to the other
 end of said casing, a lens and a reflector
 held in position by said collar, a lamp
 within said reflector, means for maintaining
 electrical connection between said contact
 110 spring and one terminal of said lamp, a bat-
 tery within said casing with its bottom con-
 tacting with said contact spring, and switch
 mechanism for connecting the inner termi-
 nal of said lamp with the upper battery
 115 terminal, said mechanism comprising an in-
 sulating base secured to said reflector, a pair
 of contact members spaced apart and mount-
 ed on said base, one of said contact members
 having a spring yieldingly engaging the
 120 inner lamp terminal and protecting said ter-
 minal from undue pressure, the other of said
 contact members being connected with the
 adjacent battery terminal, and contact
 means movable longitudinally of said casing
 to bridge the gap between said contact mem-
 bers and permit current to flow from said
 battery through said lamp; substantially as
 described.

8. In a battery hand lamp, the combina-
 125 tion of a battery, a lamp, a spring urging
 said battery toward said lamp, a reflector
 into which said lamp is threaded, an in-
 sulating base threaded to said reflector, a
 spring contacting with the inner terminal 130

- of said lamp, and means for conveying current from an adjacent battery terminal to said spring and for delivering to said base the forward thrust of said battery.
5. 9. In a battery hand lamp, the combination of a reflector, a lamp threaded therein and projecting therethrough, an insulating base secured to said reflector, and a contact member secured to said base and carrying
- 10 a spring which yieldingly engages the inner terminal of said lamp.
10. The combination of a lamp holder in the form of an insulation piece, a contact and lamp socket member carried by the said
- 15 piece, a lamp-protecting element anchored on the insulation piece and insulated from the said member and a spring contact mounted on the element.
11. The combination of a lampholder, an
- 20 insulation base and a contact and lamp socket member carried by said holder, a lamp-protecting element attached to said base and insulated from said member, and a yielding member on said element contacting with the central terminal of the lamp.
12. In a battery hand-lamp, a lamp-supporting member, a base-plate mechanically connected to and supported by said member,
- 30 conducting means mechanically connecting said base-plate and an adjacent pole of the battery, and a flexible contact member between said means and the central terminal of the lamp.
- 35 13. In a battery hand-lamp, a lamp-supporting member, an insulating base secured to said member, conducting means mechanically connecting said base and an adjacent pole of the battery, and a flexible contact
- 40 member between said means and the central terminal of the lamp.
14. In a battery hand-lamp, a lamp-supporting reflector, an insulating base threaded on said reflector about the lamp-base,
- 45 means mechanically connecting said insulating base and an adjacent pole of the battery, and a flexible contact member between said means and the central terminal of the lamp.
- 50 15. In a battery hand-lamp, a lamp-supporting member, a thrust-receiving base secured to said member, means connecting said base and an adjacent pole of the battery for rigidly transmitting forward movement
- 55 of the battery to said thrust-receiving base, and a flexible contact member between said means and the central terminal of the lamp.
16. In a battery hand-lamp, a lamp-receiving reflector, an insulating base secured
- 60 to said reflector, means connecting said base and an adjacent pole of the battery for rigidly transmitting forward movement of the battery to said base, and a flexible contact member between said means and the central terminal of the lamp.
17. In a battery hand-lamp, a lamp-receiving reflector having a rearwardly extending portion, an insulating base secured to said portion, means connecting said base and an adjacent pole of the battery for transmitting forward movement of the battery to said base, and a flexible contact member between said means and the central terminal of the lamp.
18. In a battery hand-lamp, a lamp-receiving reflector, an insulating base secured to said reflector, a plate secured to said base and engaging an adjacent pole of the battery for rigidly transmitting forward movement of the battery to said base, one side of said plate having a hollow portion to accommodate the base of the lamp, and a flexible contact member between said plate and the central terminal of the lamp.
19. In a battery hand-lamp, a lamp-supporting reflector, an insulating base secured to said reflector, a plate secured to said base and having a cylindrical extension inclosing the base of the lamp and adapted to engage an adjacent pole of the battery for rigidly transmitting forward movement of the battery to said base and through the latter to said reflector, and a flexible contact member between said plate and the central terminal of the lamp.
20. In a battery hand-lamp, a lamp-holder, an insulation base and a contact and lamp socket member carried by said holder, two annular concentric contact members secured to said base, one of said members having yielding contact with the central terminal of the lamp, a lamp-protecting element connected to the other annular member and contacting with a pole of the battery, and a switch for connecting said annular members.
21. In a battery hand-lamp, a casing, a lamp socket member carried by the casing, a dry battery, a lamp-protecting element in rigid relation between the battery and said member, said lamp-protecting element having a conductor member in contact with an adjacent pole of the battery and having a free terminal, a second conductor member yieldingly contacting with the lamp-base and the other pole of the battery and having a free terminal, said conductor members being insulated from each other, and means for connecting said terminals.

In testimony whereof I affix my signature.

CARL HAMBUECHEN.
